UNITED STATES PATENT OFFICE.

HENRY ARIENS, OF BRILLION, WISCONSIN, ASSIGNOR TO BRILLION IRON WORKS, OF BRILLION, WISCONSIN.

HOISTING DEVICE.

1,249,297.

Specification of Letters Patent. Patented Dec. 11, 1917.

Application filed May 18, 1917. Serial No. 169,433.

To all whom it may concern:

Be it known that I, HENRY ARIENS, a citizen of the United States, and resident of Brillion, in the county of Calumet and State 5 of Wisconsin, have invented certain new and useful Improvements in Hoisting Devices; and I do hereby declare that the following is a full, clear, and exact description thereof.

My invention relates to new and useful 10 improvements in hoisting devices and refers especially to such devices adapted for use by molders and the like.

The primary object of my invention is to provide a simple and economical portable 15 hoisting device, the same being especially designed for molders' use and so constructed and arranged that the labor of pouring molten metal may be readily accomplished by a single operator, thereby greatly economizing 20 in time and labor. The apparatus is suspended from any suitable overhead track system in such manner that the container or vessel can be moved from place to place longitudinally or transversely of a floor to 25 selected position over a series of molders' flasks without exerting any material force in proportion to the load, and, though the apparatus is especially designed for molders' use, it may be adapted for conveying 30 and pouring various commodities.

With the above and other objects in view, which will appear as the description proceeds, my invention resides in the novel construction, formation and arrangement of 35 parts substantially as herein described and claimed, it being understood that changes in the precise embodiment of the invention herein disclosed can be made without departing from the spirit of the invention.

40 In the accompanying drawings I have illustrated one complete example of the physical embodiment of my invention constructed according to the best mode I have so far devised for the practical application 45 of the principles of my invention.

Figure 1 is a view in front elevation of my invention, the track mechanism not being shown.

Fig. 2 is a side elevational view thereof.

50 Fig. 3 is a sectional view taken on the plane indicated by the line 3—3 of Fig. 1.

Fig. 4 is a sectional view taken on the plane indicated by the line 4—4 of Fig. 1, and Fig. 5 is a transverse sectional view 55 taken on the line 5—5 of Fig. 3.

Referring by characters to the drawings, 5 designates a pair of bail arms that terminate in receiving hooks 6 at the lower ends, said bail arms being connected at their upper ends by a yoke 7 connected with a head piece 60 8 by means of the bolt 9. This head piece 8 is fixed to the lower end of the squared adjustable guide rod 10, said guide rod being guided in the corresponding squared hollow hanger rod 11, supported by hanger 11' from 65 any suitable track conveyer.

Fixed to the lower end of the hanger 11 is the head block 12 having a pair of laterally down turned arms 13, and formed on the lower ends 14 of these arms are the 70 bearings for the transverse shaft 15, said shaft being also journaled in bearings 16 on the central portion of the head block. Mounted on the shaft 15, intermediate the central portion of the head piece 12, and 75 the arms 13 are a pair of grooved drums 17 adapted to receive the hoisting cables 18 secured at 19 to the head block 8.

For revolving the drums 17 to wind the 80 cables 18 thereupon, a chain pulley 19' is employed fixed to a shaft 20 and journaled in bearings 21 also carried by the downwardly extending arms 13 adjacent the ends thereof. This shaft 20 is in operative engagement with the shaft 15 through the 85 medium of the tooth gears 22 and 23 carried by the shafts 15 and 20 respectively.

The wheel 19' is grooved to receive an operating chain 24 which is guided thereon through means of the guiding member 25 90 carried by one of the arms 13.

Thus it will be seen that when the wheel 19' is revolved through the chain 24, the shaft 20, will, through the medium of the gears 22 and 23, revolve the drums 17, thus 95 causing the guide rod 10 to be lifted or lowered as the case may be. It is apparent that the guide rod 10 is slidable in the sleeved hanger 11 and is prevented from a swinging movement by its squared faces. 100

To govern the downward movement of the hoist, a brake band 26 is utilized engaging a brake drum 27 fixed to the wheel 19'. The brake band 26 has its ends pivoted to arms 28 formed on the inner end of the weighted 105 lever or fulcrum 29 pivotally secured at 30 to the head piece 12. As will be readily seen by reference to Fig. 4, this brake is at all times in binding engagement with the drum 27, and when it is desired to release 110

the brake, a lever 31 is employed attached to the outer end of the lever 29.

Thus it will be readily apparent from the foregoing description taken in connection with the accompanying drawings, that I have provided a simple and efficient device of this character, and while I have illustrated my invention as employed in lifting or hoisting a molder's pouring vessel 32, it 10 will be understood that my invention may be used in numerous other ways.

To adapt my invention for use in moving a flask from place to place, it is simply necessary to remove the bolt 9 detaching the bail arms 5 from the head block 8, and replace the same with a suitable hoisting hook or other device not shown.

What is claimed is:—

1. A device of the character described comprising a head piece having arms formed thereon, a guide rod carried by said head piece and adjustably guided therein intermediate the arms of said head piece, work-receiving means carried by the guide rod, hoisting drums journaled in the arms of said head piece, and hoisting cables wound about said drums and engaging said guide rod to operate the device.

2. A device of the character described comprising, in combination, a sleeved hanger rod, a guide rod slidably mounted therein, a head block fixed to the lower end of the guide rod and adapted for engagement with work to be hoisted, a head piece mounted on the lower end of the hanger rod, hoisting drums having their shafts journaled in bearings carried by the head piece, hoisting cables connected with the head block and adapted to be wound upon said drums, and means for revolving the drums to operate the device substantially as described.

3. In a portable hoisting device, the combination with a hanger rod, of a guide rod slidably carried thereby and having work engaging means on its lower end, a head piece fixed to the lower end of the hanger rod, laterally and downwardly extending arms carried by the head piece, hoisting drums intermediate the ends of said arms, means for revolving said drums, hoisting cables secured to the lower end of the guide

rod adapted to be wound upon the drums and braking means for governing the operation of said drums.

4. A device of the class described comprising a sleeved hanger rod, a guide rod slidably mounted therein, a head piece having a central portion fixed to the lower end of the hanger rod, laterally down-turned arms formed on the head piece, a pair of parallel shafts journaled in said arms, a pair of hoisting drums carried by one of said shafts, a manually operated wheel fixed to one end of the other of said shafts, gears carried by both of said shafts and in mesh with each other, and hoisting cables fixed to the lower end of the guide rod and adapted to be wound upon the hoisting drums.

5. A device of the class described comprising a sleeved hanger rod, a guide rod slidably mounted therein, a head piece having a central portion fixed to the lower end of the hanger rod, laterally down-turned arms formed on the head piece, a pair of parallel shafts journaled in said arms, a pair of hoisting drums carried by one of said shafts, a manually operated wheel fixed to one end of the other of said shafts, gears carried by both of said shafts and in mesh with each other, hoisting cables fixed to the lower end of the guide rod and adapted to be wound upon the hoisting drums, and braking means for governing the movement of the hoisting drums substantially as described.

6. A device of the character described comprising a head piece including a central guide portion and a pair of laterally down turned arms, a guide rod adjustably mounted in said central guide portion of the head piece, a head block carried by said guide rod and adapted for engagement with the work to be hoisted, hoisting means mounted between the arms and central portion of the head piece, and connections between said hoisting means and said head block of the guide rod to operate the device.

In testimony that I claim the foregoing I have hereunto set my hand at Brillion in the county of Calumet and State of Wisconsin.

HENRY ARIENS.
